UNITED STATES PATENT OFFICE.

BENJAMIN J. GEISSE, OF OAKLAND, CALIFORNIA.

VALVE LIFTER.

Application filed June 15, 1927. Serial No. 198,950.

This invention relates to internal combustion motors and particularly pertains to a valve lifting device for compressing the valve springs so that they may be disconnected from the valve stems and the valves removed.

It is the principal object of the present invention to generally improve and simplify devices of the character referred to whereby to provide a valve lifter capable of operation in connection with L-head motors and designed so that it will be capable of operation in compressing valve springs when the latter are positioned so that it is difficult to gain access thereto.

In carrying out this invention into practice, I provide a bail-shaped frame of sufficient dimensions to embrace the usual projecting manifolds of an engine and place its ends in operative position relative to the opposite ends of the valve. To these ends of the frame devices are pivoted to engage the valve and valve spring, which devices are operative so that they may be moved relatively closer together to compress the spring and maintain it compressed. The compressing devices of the frame are pivoted to the frame as defined so that the latter may be positioned to avoid the engine accessories when the latter render it difficult to gain access to the valves.

One form which the invention may assume is exemplified in the following description and illustrated by way of example in the accompanying drawings, in which:

Fig. 1 is a side elevation of a valve lifter embodying the preferred form of my invention and disclosing it as operatively connected to a valve and spring.

Fig. 2 is a similar view showing the valve lifter after it has been operated to compress the valve spring.

Fig. 3 is a perspective view of my valve lifter showing certain details of construction.

Referring more particularly to the accompanying drawings, 10 indicates a valve lifter or valve spring compressor capable of use in connection with automobile engines to compress the valve spring so that the keeper in the valve stem may be removed to permit the extraction of the valve from the cylinder block.

In the drawings wherein the preferred form of my device is disclosed 11 indicates

a bail-shaped rigid frame formed of any suitable material having a vertical portion 12 and horizontal legs 14 and 14^a. When in use the frame 11 is arranged vertically so that the legs 14 and 14^a will extend horizontally. The distance between these legs is sufficient to permit them to straddle the projecting portion of a cylinder block as illustrated in Figs. 1 and 2. In this position the lower leg 14^a will be disposed in a position so that a bifurcated cup receiving member 15 may engage the underside of the valve spring cup while the upper leg 14 will be disposed a distance above the head of the valve as illustrated.

Reference being had to the drawings it will be noticed that the bifurcated cup receiving member 15 is formed in two parts having circular bosses 15^a disposed between the legs of a clevis 15^b carried by the extremity of the lower leg 14^a of the frame 11. It will be noted that the bosses 15^a of the portions of the cup receiving member are offset so that the cooperative portions will be disposed in the same plane. The bosses 15^a of the cup receiving member may pivot about a pivot pin 15^c extending between the legs of the clevis 15^b. A wing nut 15^d is arranged on the pivot pin 15^c to clamp the cup receiving member 15 relative to the leg 14^a of the frame 11. The engaging faces of the bosses of the two portions of the cup receiving member are preferably knurled to maintain them relatively fixed when the nut 15^d is tightened.

The object of making the cup receiving member 15 in two parts is so that it can be adjusted so that it will accommodate different sizes of valve spring nuts. Likewise it is pivoted to the frame so that it may be arranged at any desired angle relative thereto to facilitate its engagement with the valve spring cup.

The upper leg is pivotally connected as at 16 to a guide sleeve 17. The pivotal connection between the guide sleeve 17 and the leg 14 includes a horizontally extending arm 18 on the guide sleeve 17 which is pivoted to a clevis 19 at the extremity of the leg 14 of the frame 11. The clevis 19 is disposed horizontally so that the guide sleeve 17 may pivot in a horizontal plane with respect to the frame 11. The pivotal points of the guide sleeve and of the cup receiving member 15 are disposed in alignment.

Reciprocably mounted in the guide sleeve 17 is a valve engaging pin 20. The lower end of this pin 20 is conical so that it will center in the center hole of the valve head. Between its ends the valve engaging pin 20 is formed with a plurality of transverse drilled openings 21 which align with a longitudinal slot 22 in the sides of the guide sleeve 17.

One end of a pair of links 23 is connected with the valve engaging pin 20 by means of a cotter key 24 extending through the ends of the links and through one of the drilled openings 21. The provision of the slots 22 permits the links 23 to be engaged with the valve engaging pin 20 without interfering with the latter's vertical reciprocation. The other end of the links 23 pivotally connect to a fulcrum lever 25 at a point intermediate its ends. One end of this fulcrum lever is pivoted to the upper end of the guide sleeve 17 at one side thereof as illustrated.

It will be noticed that the pivoted end of the lever 25 is bifurcated so as to align with the links and to engage opposite sides of the lug on the guide sleeve 17 to which it is pivotally connected. This bifurcated end of the lever is curved so that in one position the lever will align with the upper leg 14 of the frame 11. When in this latter position the pivotal point of connection between the links and the lever will be beyond center or beyond a line drawn between the pivotal point of the lever and the point of connection between the links and the valve engaging pin 20 so that upward pressure on the valve engaging pin 20 will not tend to raise the lever.

In operation of the device, it is constructed and assembled substantially as shown in the drawings and in compressing a valve spring the frame 11 is arranged in a vertical position with the lower leg 14^a inserted beneath the valve spring cup and the upper leg arranged over the valve. In some instances there is not sufficient clearance to permit the frame 11 to extend out transversely of the cylinder block and for this reason the guide sleeve 17 and the cup receiving member 15 may be arranged at an angle to the frame to enable them to be aligned with the valve. When properly positioned the nuts 15^a are tightened.

In order to accommodate the different diameters of spring cups, the portions of the cup receiving member 15 may be spread apart or contracted to properly engage the cups. It is seen that these side portions are triangular in section so that they will embrace the cup and at the same time abut against the bottom of the cup.

When properly positioned the lever 25 is drawn downwardly, lessening the distance between the end of the valve engaging pin 20 and the cup receiving member 15. As the end of the pin 20 engages the head of

the valve which is seated, the entire frame 11 will move vertically as the valve spring is compressed. When the valve spring is fully compressed the pivotal point of connection between the links and the lever will be disposed beyond center, locking the pin 20 in place. The keeper in the valve stem may then be removed and the lever 25 raised to release the valve spring. The device may then be removed and the valve ground.

In order to accommodate different lengths of valves the point of connection between the links and the pin 20 may be changed to suit the different length of valves, that is, the cotter key may be withdrawn and the links connected to the pin by connecting the links to any one of the various openings along the pin 20.

After the valve has been ground and it is desired to compress the spring in order to re-position the keeper in the valve stem, the cup receiving member 15 may be engaged between any of the convolutions of the valve spring at the lower end thereof, while the engaging pin 20 is abutted against the head of the valve as previously described. The lever is then pressed downwardly to compress the valve spring.

I prefer that the cup receiving member 15 be magnetized so that it will attract the cup 15. This is preferred for the reason that in compressing the valve spring to re-position the keeper and connect the spring to the valve, the cup receiving member 15 is engaged with the lower convolutions of the valve spring and not with the cup because it is very difficult to force the member 15 beneath the cup when the latter is disconnected from the valve stem. Therefore, after the valve spring is compressed the cup is arranged on the valve stem and moved upwardly thereon to the bottom of the spring. By having the member 15 magnetized it will hold the cup in position so that the operator will be free to position the keeper without having to hold the cup in place with one hand.

From the foregoing it is obvious that I have provided a comparatively simple and inexpensive valve lifter capable of adjustment in several different manners so as to make its use universal with respect to L-head motors regardless of their dimensions or the positioning of accessories thereon.

It is also apparent that by the use of my device that the operation of compressing the valve springs to disconnect them from the valve will be greatly expedited.

While I have shown the preferred form of my invention, it is to be understood that various changes may be made in its construction by those skilled in the art without departing from the spirit of the invention, as defined in the appended claims.

Having thus described my invention, what

I claim and desire to secure by Letters Patent is:

1. A device of the character described comprising a bail-shaped frame to embrace the projecting portion of a cylinder block, bifurcated spring engaging means formed in two relatively adjustable sections pivotally mounted at and extending from one end of the frame, a guide member pivotally supported at the other end of the frame in alignment with the spring engaging means, a reciprocable valve engaging member slidably disposed in said guide for reciprocation toward and away from the spring engaging means, and means for reciprocating said engaging member toward and away from the spring engaging means.

2. A device of the character described

comprising a bail-shaped frame to embrace the projecting portion of a cylinder block, 20 bifurcated spring engaging means formed in two relatively adjustable sections pivotally mounted at and extending from one end of the frame, a guide member pivotally supported at the other end of the frame in 25 alignment with the spring engaging means, a reciprocable valve engaging member slidably disposed in said guide for reciprocation toward and away from the spring engaging means, means for reciprocating said engaging member toward and away from the spring engaging means, and means for automatically locking said valve engaging member in its most extended position toward the spring engaging means. 30

BENJAMIN J. GEISSEER.
